UNITED STATES PATENT OFFICE.

WALTER F. BURTON, OF CHIPPEWA FALLS, WISCONSIN.

DESIGN FOR LATH-MACHINE BED.

Specification forming part of Design No. 6,703, dated June 17, 1873; application filed June 5, 1873.

To all whom it may concern:

Be it known that I, WALTER F. BURTON, of Chippewa Falls, in the county of Chippewa and State of Wisconsin, have invented a new and original Design for a Portable Lath-Machine, and I do hereby declare the following to be a full, clear, and exact description of the same, reference being had to the accompanying drawing forming a part of this specification, in which the figure represents a perspective view.

The nature of my design is fully represented in the accompanying drawing, and relates to the bed-plate of portable gang lath-machines.

A is the bed-plate channeled at a, and subjacent thereto, having the downward projection a¹; also, having the channel a² and subjacent thereto the piece a³; between these in-

tervenes the riser a. The piece a¹ supports the shaft of the saw, and the piece a³ the shaft of feed-roll.

Ordinarily these pieces are made separate, are cumbersome and offend the eye, while mine, being made of the same piece, present an aspect of unity, and a graceful outline which is pleasing to the mechanical eye.

Having thus described my invention, what I claim as new, and desire to secure by Letters Patent, is—

The design as above shown and described.

The above specification of my invention signed by me this 21st day of May, A. D. 1873.

WALTER F. BURTON.
